S. H. LIFTON

BRIEF CASE

Filed Aug. 4, 1923

UNITED STATES PATENT OFFICE.

SAMUEL H. LIFTON, OF BROOKLYN, NEW YORK.

BRIEF CASE.

Application filed August 4, 1923. Serial No. 655,567.

To all whom it may concern:

Be it known that I, SAMUEL H. LIFTON, a citizen of the United States, and resident of Brooklyn, in the city and State of New York, have invented new and useful Improvements 5 in Brief Cases, of which the following is a specification.

This invention relates to brief cases and similar devices having a body member, and a 10 closure therefor in the form of a flap adapted to overlap the upper edges of the body member.

In devices of the character described herein, having a closure flap, it is necessary to 15 hold the flap upward and outward by one hand while inserting articles into the case, or removing them therefrom.

Considerable difficulty is frequently had 20 under such conditions in properly arranging the contents within the case and in sorting out, or selecting from, the contents of such case without removing the entire contents.

The invention has for its primary object to 25 provide a device of the character stated that is simple and strong in construction, durable in use, and adapted to enable the contents of such a case to be readily inserted therein in any desired relation to each other, and selectively removed therefrom readily and 30 quickly.

For accomplishing such purpose, the invention comprises a brief case, or similar device, provided with a closure flap that readily adjusts itself to a vertical position when 35 released at its free margin from the body of the case, thereby enabling the user to employ both hands, if so desired, in placing any articles within the case in their proper relation to each other, or to remove therefrom any desired article without removing the entire 40 contents of the case.

With the foregoing and other objects in view, hereinafter stated, the invention consists of the novel construction, combination, 45 and arrangement of parts hereinafter more specifically stated, and illustrated in the accompanying drawings, wherein is shown a device embodying the structure of the invention in its preferred form, but it is to be understood that changes, variations, and modifications may be resorted to without departing 50 from the scope of the invention.

In describing the invention in detail, reference is had to the accompanying drawings, 55 which form a part of this specification, wherein like characters of reference indicate

corresponding parts throughout the several views, and wherein:

Fig. 1 is a perspective view of a brief case embodying my invention, showing the closure flap in open position in full lines, and indicating by dotted lines the position of the flap when closed; 60

Fig. 2 is a vertical transverse section taken on the line 2—2 of Fig. 1, and illustrating by dotted lines the closure flap in closed position, and in a position intermediate its closed and open position; 65

Fig. 3 is a side elevation of the inner surface of a closure flap and one side of a brief case embodying the invention, in a modified form; 70

Fig. 4 is a view similar to that shown in Fig. 3, illustrating a further modification of the invention; and 75

Fig. 5 is a horizontal section taken on the line 5—5 of Fig. 1.

The body of the brief case shown in the drawings is of the usual construction, comprising front cover member 1 and back cover member 2, the latter having a closure flap 3 formed therewith. The front and back cover members are connected by means of gusset members 4, and if desired an intermediate wall 5 may be connected with the gusset 80 members. 85

The gusset members are secured to the cover members at their outer margins by means of rows of stitching 6.

The closure flap is shown provided with a lock section 7 which engages a corresponding lock section 8 secured to the front cover member 1. The flap is also provided with strap members 9 which engage buckle members 10 secured to the front cover member 1 90 in the usual manner.

In order to enable the closure flap to automatically assume a vertical position as soon as said member is disengaged from connection with the front cover member of the case, the closure flap and a portion of the back cover member 2 are provided with a flexible resilient member 11 which extends downwardly below the lower margin of the closure flap, so as to have a bearing on both the back cover member and the closure flap. 100

The member 11 may be of any suitable form, such as a thin band or wire, made of metal, or other material having similar capabilities.

As shown in Fig. 1, the resilient member is 110 made in two sections, each section extending

along the lateral margin of the closure flap and part-way down the margin of the back cover of the case, with the upper end thereof extending part-way along the front margin 5 of the closure flap, so as to hold the entire flap in a vertical position when released from engagement with the front cover member of the case.

While such construction is suitable for 10 carrying out the invention, the resilient member may be formed of one continuous piece of metal extending entirely around the outer margin of the closure flap and along the upper lateral margin of the back cover member, as shown in Fig. 3.

The resilient member 11 may be secured 20 in place against the inner surface of the back cover member and closure flap in any suitable manner, preferably by means of a cover or lining 14, the outer margin of which may be secured together with the outer margin of the back cover member and the outer margin of one of the gussets 4, as shown in Fig. 5, with a portion of said 25 cover or lining secured to the back cover member by means of a row of stitching 15. The member thus covering the flexible member is preferably extended entirely across the inner face of the back cover member, 30 although that is not an essential feature of the invention.

The resilient member 11 serves not only 35 as means for automatically raising the closure flap when released from the front cover member, but also as a reinforcing member for holding the outer margin of the flap in shape so as to prevent it from twisting or curling. The reinforcing feature of 40 said member may be employed to reinforce the back cover member 2 by continuing the resilient member around the entire outer margin of the closure flap, and the entire outer margin of the back cover member, as 45 shown in Fig. 4.

45 The case is carried in the usual manner by means of a handle or strap 12.

When in use, brief cases are generally 50 handled roughly, and frequently they are thrown down carelessly on their back cover member, and consequently that portion of the case is subjected to greater wear than the 55 remaining portions thereof. By extending the resilient member entirely around the margin of the closure flap and the outer margin of the back cover member, the back cover member and the cover flap of the brief case are specially protected from injury.

When it is desired to have access to the

interior of the case, and the closure flap is released from engagement with the front cover member, the closure flap instantly springs backward automatically into the position shown in full lines in Figs. 1 and 2; the user of the case is then enabled to use both hands while examining the contents of the case and remove any desired article therefrom, without withdrawing the entire contents therefrom, as is ordinarily the case where a flexible flap is required to be held outward by one hand of the user when the brief case is to be filled, or when any desired article is to be removed therefrom.

The resilient member 11 is preferably made of sufficient flexibility to readily bend between the point of its attachment to the 75 back cover member and the front margin of the flap, as indicated by the dotted lines 13 in Fig. 2, which shows the position assumed by the closure flap intermediate its position when locked in engagement with the front 80 cover member, and its vertical position.

The convenience and ease with which the brief case can be filled, or any portion of its 85 contents examined and removed is increased by virtue of the fact that the closure flap spring member, by being extended around the outer margin of the back cover member, enables said cover member to be held evenly in a vertical plane coincident with that of the closure flap, thereby preventing any 90 bulging or sagging of the back cover member and closure flap.

What I claim as new and desire to secure by Letters Patent is:

1. A brief case, comprising a body having 95 a front cover member, and a back cover member provided with a closure flap, and resilient means connected with said closure flap and back cover member, adapted to automatically lift said flap and open said 100 body.

2. A brief case, comprising a body having 105 a front cover member, and a back cover member provided with a closure flap, and a resilient flap opening member secured to the outer margin of said flap and back cover member.

3. A brief case, comprising a body having 110 a front cover member, and a back cover member provided with a closure flap, and a resilient band secured to the outer margin of said flap and back cover member.

In testimony that I claim the foregoing as my invention, I have signed my name hereunder.

SAMUEL H. LIFTON.
